UNITED STATES PATENT OFFICE.

WILLIAM W. SMITH, OF BUFFALO, NEW YORK, ASSIGNOR OF ONE-HALF TO WILLIAM C. KIDDER, OF BUFFALO, NEW YORK.

PROPELLER.

1,380,431.

Specification of Letter's Patent. Patented June 7, 1921.

Application filed March 22, 1920. Serial No. 367,643.

To all whom it may concern:

Be it known that I, WILLIAM W. SMITH, a citizen of the United States, residing in Buffalo, in the county of Erie and State of New York, have invented new and useful Improvements in Propellers, of which the following is a specification.

This invention relates to a driving propeller or rotatable screw for propelling air 10 craft or water craft, and relates more particularly to a reinforced all-metal propeller for aeroplanes.

One of the objects of the invention is to provide a light and yet strong propeller 15 which is weatherproof and waterproof and cannot be warped or bent out of shape, whereby the propeller blades are enabled to precisely retain their original balance and pitch. A further object of the invention is to provide the propeller blades with suitable 20 bracing or stiffening webs for taking up the stresses due to the thrust and twisting of the propeller. A still further object of the invention is to provide light hollow propeller 25 blades of streamline form whereby the desired thrust of the propeller is obtained with a minimum of circumferential air resistance. Further objects and advantages will appear more clearly in the following specification and accompanying drawings wherein:

Figure 1 is an end view of the improved reinforced propeller. Fig. 2 is a transverse section through the blades of the propeller taken on line 2—2, Fig. 5. Figs. 3 and 4 are transverse sections through one of the propeller blades taken on correspondingly numbered lines of Fig. 1. Fig. 5 is a section taken through the hub of the propeller in a plane parallel with the axis of the propeller 40 on line 5—5, Fig. 2.

Similar characters of reference refer to like parts throughout the several views.

This invention is applicable to the screw propulsion of either water and air craft 45 and may also be associated with rotary or force pumps or blowers which handle any kind of fluid such as air or water. The drawings, however, only disclose the invention as applied to an aeroplane propeller, the same being shown in end elevation in Fig. 1. The numeral 10 represents the hub or central thickened part of the propeller, said hub being provided with a central longitudinal hole 11 which is adapted to receive a pro-

peller shaft, not shown, upon which the 55 propeller is adapted to rotate. The hub 10 is further provided with a suitable key way 12, whereby the propeller is constrained to rotate with the propeller shaft. The longitudinal central part of the hub is suitably 60 hollowed or cored out at 13 for the purpose of lightening the propeller without however, decreasing the overall length of the hole 11. It is obvious that if the overall length of the hole 11 were short, the 65 propeller would tend to become loosened or to rock on the propeller shaft after considerable usage, whereas by hollowing the hub at 13, the said hub is not only rendered 70 lighter but the only metal which is removed 75 is that which has no appreciable effect in preventing the propeller from rocking on the propeller shaft. The hub of the propeller may also be provided with a circumferential row of longitudinal bolt holes 14, which are adapted, in a manner common in 80 the aeronautic art, to receive suitable bolts which pass into a suitable flange on the propeller shaft.

Connected preferably integrally with said 85 hub 10 are two or more hollow propeller blades, each of which comprises an inclined rear thrust face 15 and a front blade face 16, the former being the driving face which compresses the air layers immediately adjacent thereto, as the propeller is caused to revolve, thereby creating the "thrust" of the propeller. The front blade face 16 is, of course, caused, when the propeller is rotated, to float in a partial vacuum area, and therefore the shape of said front face 16 is arranged to be of streamline form so as to prevent undue eddy air currents from curling around the "cutting" edge 18 of the 90 blade and thereby impairing the efficiency of 95 the low pressure area, the action being similar to the action of the air currents on the main wings of an aeroplane. The outer ends and the adjacent edges of the companion faces 15 and 16 of each blade are 100 preferably connected integrally together so as to present a smooth unbroken surface around the entire perimeter of the blade, thereby excluding all moisture from the 105 hollow portion of the blade and also providing for a minimum of skin and head-on air resistance of said blade.

Arranged longitudinally within the hol-

low part of each propeller blade is a bracing or stiffening rib 20, whose opposite edges are preferably integrally secured to the opposite faces 15 and 16 of said blade 5 and whose opposite ends are secured respectively to the hub 10 and the outer tip 19 of said blade. The plane of this stiffening rib 20 is parallel to the axis of the propeller, that is of the hole 11, so that the strains 10 which are set up by reason of the thrust of the propeller are carried by this stiffening rib, whose plane therefor is parallel to the strain imposed upon it. Projecting outwardly from each longitudinal stiffening 15 rib 20 is a laterally extending rib 21 which is preferably integrally secured on its opposite edges to the opposite faces 15 and 16 of each propeller blade and whose opposite ends are preferably integrally secured 20 respectively, as the case may be, either to the rib 20 and the front or the rear edge of the propeller blade. The plane of these laterally extending ribs 21 is, similarly to the ribs 20, *i. e.*, parallel to the axis of the propeller. Each of these lateral ribs 21 however, is arranged at an angle relatively to its companion longitudinal rib 20. The angle may be any desired number of degrees 25 up to 180 degrees, but in the preferred arrangement shown in the drawings, these lateral ribs extend outwardly from their companion longitudinal ribs 20 in a manner similar to that in which the finer stiffening veins extend like a fan out from the stem of 30 a plant leaf. These laterally extending ribs 21 serve to sustain those twisting strains of the propeller blade which tend to alter the pitch or angle of said blade. These twisting strains are caused by un- 35 equalized pressures at different parts of the faces of the blades, resulting from a number of causes which need not be here discussed except to state in a general way that the principal air pressure is exerted just behind the leading edge 18 of each propeller 40 blade and not the geometrical center of the face of the blade. Where the entire propeller is cast in one piece, it is of course, necessary to remove the core sand from the hollow 45 pockets of each blade and for this purpose suitable holes 23 are formed in the appropriate parts of the blade walls and are suitably plugged up by means of plugs 24 after the said core sand has been removed. It is 50 obvious however, that these plugs 24 may be dispensed with, where the propeller is cast 55

or forged in a number of sections and then welded together.

This improved propeller is manifestly strong and **stiff** by reason of its internal 60 bracing and yet is light and waterproof. The pitch and balance of the propeller blades is not liable to variation and the outer surface of the propeller may be given a smooth buffed finish which is not only 65 permanent but permits of a low frictional resistance and renders the propeller very attractive in appearance. The hub of the propeller is rendered very light without weakening the strength of the same or allowing the propeller to get loose on its 70 shaft. Furthermore, the propeller can be constructed entirely by machinery with an automatically accurate precision that is not possible with an ordinary laminated wood 75 propeller which requires very skilled manual labor for all operations except the roughing cuts. Furthermore, inasmuch as this improved propeller may be constructed of metal which does not vary appreciably 80 in specific gravity, the propeller as it comes from the final finishing machines needs but little to balance it accurately, whereas the forms of wooden propellers have to be altered considerably to obtain the all vital 85 balance of the propeller.

The whole propeller can be cast in one piece with various numbers of blades and is preferably made from a special formula of alloyed metals, the greater portion being 90 pure aluminum, the other metals of the alloy being added to lighten and strengthen and bring it to a suitable degree of hardness for smooth finish and to secure a tensile strength of over 18,000 pounds. 95

I claim as my invention:

1. A propeller having hollow blades reinforced by longitudinal stiffening ribs, and lateral stiffening ribs extending outwardly from said longitudinal stiffening ribs and at 100 an oblique angle relatively thereto.

2. As an article of manufacture a propeller having hollow metal blades reinforced by central longitudinal ribs arranged within the hollow part of said blades; and 105 lateral stiffening ribs also arranged within the hollow part of said blade and extending out from both sides of said longitudinal ribs and at an oblique angle relatively thereto.

WILLIAM W. SMITH.
